UNITED STATES PATENT OFFICE.

EDWARD ERICKSON, OF BEVERLY, MASSACHUSETTS, ASSIGNOR TO UNITED SHOE MACHINERY CORPORATION, OF PATERSON, NEW JERSEY, A CORPORATION OF NEW JERSEY.

STITCH AND UPPER CLEANING MACHINE.

1,402,752.

Specification of Letters Patent. Patented Jan. 10, 1922.

Application filed May 11, 1918. Serial No. 233,875.

To all whom it may concern:

Be it known that I, EDWARD ERICKSON, a citizen of the United States, residing at Beverly, in the county of Essex and State 5 of Massachusetts, have invented certain Improvements in Stitch and Upper Cleaning Machines, of which the following description, in connection with the accompanying drawings, is a specification, like reference 10 characters on the drawings indicating like parts in the several figures.

This invention, among other uses, is especially applicable to shoe finishing machinery. The invention will be described 15 with particular reference to a machine of the type known to the trade as a stitch and upper cleaning machine, although it is not intended to limit the invention thereby.

A general object of the invention is to 20 provide an improved machine of this class by means of which the quality of work may be improved and the speed of operation increased.

After a shoe has been completed and before it is ready for packing, it is necessary 25 to remove stains and surface dirt from the uppers and to brush out dirt and superfluous wax which may have been lodged in the rand crease. In cleaning the uppers, the 30 practice has been to moisten them by application to a moistened brush or wet sponge and then to apply the shoe to a soft cleaning brush usually constructed of cloth and sometimes termed a "yarn" brush. If, however, 35 the moistening brush and cleaning brush are mounted upon the same shaft, it is impossible to drive this shaft at a speed which will be suitable for both brushes for if the speed is great enough to suit the requirements of the cloth brush, then it will 40 be so great that water will be thrown from the moistening brush, and if the speed is adapted for moistening, it will not be sufficiently great for the proper operation of 45 the cleaning brush.

Various arrangements have been proposed to overcome this difficulty and machines have been constructed in which two parallel shafts were employed and others in which 50 the shafts were telescopically arranged. Inasmuch as it is necessary to change the brushes frequently, and especially the cleaning brush, such machines have usually been designed with the tools overhanging the

shaft bearings so that they have been separated by a considerable distance. This is necessarily an awkward arrangement for the operator and increases the time required for cleaning each shoe. These difficulties are overcome in the illustrated embodiment of 60 the invention by mounting the two tools upon independent shafts which are arranged so that working faces of the two tools will be substantially in alinement, with the tools on the near opposing ends of the shafts and 65 closely adjacent to one another. This enables the operator to decrease the time required for moving the work from one tool to the other and permits the two shafts to be driven at the desired speeds from the 70 main shaft and work can be simultaneously performed by both tools on different portions of the articles. It will be obvious, however, that such an arrangement, although desirable for the reasons pointed 75 out, entails an additional difficulty when it becomes necessary to remove or change one of the brushes.

An important feature of the invention relates to an arrangement allowing displacement of one of the shafts with respect to the other so that either tool may be readily removed. In the illustrated arrangement, one of the shafts is mounted upon an adjustable bracket which is capable of movement about 80 a center located at the side of the tool shaft toward the driving shaft, thus maintaining the driving belt in undisturbed position and allowing the removal of either brush without reference to the space between the opposing ends of the shafts. This feature involves the additional advantage that the working peripheral faces of the two tools may be brought into alinement whenever, because of the design of the tools or because 85 of the uneven wearing away of the tools, they are of different diameters.

Another feature of the invention relates to the arrangement of the stitch cleaning brush, which is commonly a short stiff 100 bristled brush and is preferably driven at a much higher speed than either of the other operating tools, to enable facile transference of work thereto from the other tools and vice versa. In the preferred arrangement, 105 this brush is mounted upon a separate shaft which is angularly related to the shafts upon which the other two operating tools

are mounted and which is driven by an independent belt from the main driving shaft. Means are then provided for adjusting the angular relation of this brush 5 with respect to the other tools and preferably this adjustment is about the center of the driving pulley. This arrangement allows adjustment without interfering with the tension of the driving belt and is of 10 material importance from the operator's standpoint.

Further features of the invention will appear from a consideration of the following specification, describing the preferred embodiment of the invention, taken in connection with the accompanying drawings, in which,

Fig. 1 is a front elevation with portions of the casings broken away;

Fig. 2 is a vertical section taken on the line 2—2 of Fig. 1 and looking at the right hand end of the machine;

Fig. 3 is a plan view of the machine;

Fig. 4 is a front elevation of the main driving shaft showing the belt shifter somewhat more in detail; and

Fig. 5 is a detail view taken on the section line 5—5 of Fig. 2.

The parts of the machine are supported by 30 a suitable standard 10 carrying near its base a main driving shaft 12 supported in suitable bearings and provided at its right hand end with fast and loose pulleys 14 and 16, and along its length with driving pulleys 18, 35 20 and 22. A hand lever 24 in convenient position at the front of the machine is suitably connected to a belt shifter 26 which, for the sake of illustration, is shown as of 40 the type shown and described in Letters Patent of the United States No. 1,136,116, granted April 20, 1915, upon an application of F. M. Furber.

At the upper end of the standard 10 there is provided a casing 30 having a hinged cover 32 enclosing the operating tools and 45 an outlet 33 to allow connection to an exhaust system if desired. This casing is extended in a bracket 34 to provide bearings for a shaft 36 supporting a cleaning tool 38 which will preferably be in the form of a cloth or a yarn brush. This may be retained 50 upon the shaft in any suitable fashion, for example, by means of a member 40.

Mounted at the right side of the casing 30 55 is an adjustable bracket 42, best shown in Figs. 1 and 2, which provides bearings for a shaft 44 supporting at its inner end a moistening brush 46 which is retained upon its shaft in similar fashion. Water is applied to this brush from a tank 48 through 60 a wick 50 bearing against the periphery of the brush. The tank and its wick are adjustable in a horizontal plane toward and away from the brush and may be clamped in 65 adjusted position by means of a thumb screw

52. The casing 30 is provided with a curved slot 54 formed as an arc of a circle struck preferably about the axis of the driving shaft 12 as a center. Clamping bolts 56 and 58, which are provided with plates 60 and 70 with suitable handles 62 and 64 for tightening the bolts, co-operate with the overhanging sides of the slot 54 to hold the bracket 42 in adjusted position. A suitable stop may be provided to limit the outward movement of the bracket. This arrangement permits the bracket 42 together with its shaft 44 and the brush 46 to be moved forward to a position such as that indicated by dotted lines in Fig. 2, where its tool will be 80 completely out of alignment with the tool 38 and will thus permit the ready removal of either of the tools from their respective shafts. Inasmuch as the movement is about a center on the side of the tool shaft toward 85 the driving shaft and within the loop of the belt, the tension of the belt 66 connecting the pulley 18 with the shaft 44 will not be appreciably altered by such a movement and when the bracket has been moved back into 90 the desired operative position, the machine is ready for immediate use without further attention. This belt 66, as well as the belt 37 connecting the driving pulley 20 with the shaft 26, is enclosed within casings 68 of well 95 known construction, parts of which are detachably retained in position by means of spring clamping devices shown in dotted lines in Fig. 1. By means of this arrangement, the moving parts of the machine are 100 enclosed and danger of the operator's garments catching in the machine is reduced to a minimum. It should be noted that the adjustment of the bracket 42 also allows the working faces of the tools 46 and 38 to be 105 brought into alignment (see Figs. 2 and 3), thus greatly facilitating the presentation of work successively to the tools and taking care of difference in design or uneven wear of the tools.

Adjustably mounted upon an ear 70 formed upon the bracket 34 is a support 72 forming a bearing for a shaft 74 upon which is mounted a stiff short bristled stitch cleaning brush 76. This shaft is provided 115 with a pulley 78 connected by means of a belt 80 with a driving pulley 22. A curved slot 82 in the ear or flange 70 is described upon an arc of a circle whose center is the center of the pulley 78. The center of this pulley 78 is preferably approximately vertically above the shaft 12 so that the belt will run evenly and will not be disturbed by adjusting of the stitch brush. A casing 84 which covers the upper side of 125 the brush 76 is adjustably retained in position by means of a clamping nut 86 passing through a slot in said casing. It will be observed that the angular relation of the shaft 74, carrying the stitch cleaning brush, 130

- to the shaft carrying the moistening and cleaning brushes greatly facilitates presentation of work thereto, either before or after it has been presented to the other brushes, 5 and the provision for angular adjustment of the same enables the operator to suit his personal requirements and to put the stitch cleaning brush in the position which is most desirable for his own particular use.
- 10 If desired, a receptacle 92 for naphtha, or any other cleaning agent, may be mounted upon a bracket 90 attached to the casing 30 so that any cleaning operation which may be needed may be carried out by the simple 15 moistening of the upper and may be effected by the same operator and at the same time. For the sake of illustration, there has been shown in the drawings, a dispensing receptacle 92 of the type shown in Letters Patent 20 No. 1,236,421, granted August 14, 1917, upon an application of F. M. Furber, but it will be obvious that any other suitable receptacle may be substituted therefor.

As hereinbefore stated, the invention is 25 not limited to use for cleaning the uppers and stitches of boots and shoes. Obviously other articles, whether in the form of completed products or material which is to be afterwards made up into a completed product, 30 can be cleaned with facility by the present machine. Owing to the fact that the two tools or members 38, 46 are in very close relationship and present operating surface portions which are substantially in the 35 same plane an article, whether a shoe or something else, may have different portions thereof simultaneously acted upon by the two members, thus saving time. For instance, supposing the article is a shoe or 40 a strip of leather, that article can be moved along while in operative contact with both of the wheels 38, 46 and in such direction that the wheel 46 operates first and then as the article is moved along, the portion 45 which has just been moistened by the wheel 46 is cleaned or dried or polished by the wheel 38. It will therefore be understood that to facilitate operation in the manner

described, it is of particular importance 50 that the two operating members shall have their operating surface portions in substantially the same plane and in such proximity to each other as to enable a shoe or other article to be presented to both members for simultaneous operation at different places, 55 one operation preparing the article for the next operation.

The operation of the machine will be apparent from the preceding description and, while I have herein shown and described 60 one particular embodiment of the invention, it will be understood that my invention is not limited to this particular arrangement but that its scope is defined in the appended 65 claims.

Having thus described my invention, what I claim as new and desire to secure by Letters Patent of the United States is:

1. In a machine for cleaning shoe uppers, in combination, a rotary brush to prepare 70 a shoe upper for cleaning, another rotary brush in close juxtaposition thereto to clean the prepared shoe upper as fast as it leaves the preparing brush and on the same presentation of the shoe, one of said brushes being 75 bodily adjustable to aline the working faces of the brushes for simultaneous operation on a shoe, and drive mechanism to rotate said brushes in any position of relative adjustment.

2. In a machine for cleaning articles, in combination, a rotary shaft arranged to receive any one of several brushes of various diameters, another rotary shaft to receive a brush and position it in close juxtaposition 85 to a brush on the first shaft so that one of the brushes may progressively prepare an article and the other will progressively act on the article as fast as it is so prepared, one of said shafts being bodily movable to aline 90 the working faces of the brushes regardless of their relative diameters, and a clamp to hold the movable shaft in adjusted position.

In testimony whereof I have signed my name to this specification.

EDWARD ERICKSON.
